UNITED STATES PATENT OFFICE.

WILLIAM KAMPFER, OF BROOKLYN, NEW YORK.

DESIGN FOR A GAME-BOARD.

SPECIFICATION forming part of Design No. 26,391, dated December 8, 1896.

Application filed September 12, 1896. Serial No. 605,674. Term of patent 3½ years.

To all whom it may concern:

- Be it known that I, WILLIAM KAMPFER, a citizen of the United States, and a resident of Brooklyn, in the county of Kings and State of New York, have invented a new and original Design for a Game-Board, of which the following is a full, clear, and exact description, reference being had to the accompanying drawing.
- This invention relates to a new and original design for a game-board which is fully represented in the accompanying drawing.
- The drawing is a perspective view of my game-board.
- A is the base of my new design for a game-board, which is of a circular form. Upon the outer edge of said base is mounted a peripheral ring or rim B, which is extended upward from the said base part and forms an inclosure for a series of triangular compartments.

Extending upwardly from the central portion of the said base A is a plurality of plates C, which plates are so arranged with relation to each other that they form a series of triangular compartments or pens D.

Having thus described my invention, what I claim as new, and desire to secure by Letters Patent, is—

The design for a game-board as herein shown and described.

In testimony that I claim the foregoing as my invention I have signed my name, in presence of two witnesses, this 2d day of September, 1896.

WILLIAM KAMPFER.

Witnesses:

C. SEDGWICK,
B. McCOMB.
